UNITED STATES PATENT OFFICE.

ANTON L. GRUBMAN, OF BELLE HARBOR, NEW YORK, ASSIGNOR TO VOICES, INCORPORATED, OF NEWARK, NEW JERSEY, A CORPORATION OF DELAWARE.

SOUND-PRODUCING DEVICE.

Application filed January 15, 1925. Serial No. 2,481.

This invention relates to sound-producing devices, and more particularly to gravity automatic sound-producing devices of that type which are now generally used in connection with dolls or other toys, for simulating a characteristic cry.

More particularly, my present improvements relate to that class of such sound-producing devices wherein there is provided a gravity movable member for expelling air under pressure from a chamber through a sounding reed and a valve for controlling the emission of the sound produced, together with means on the air expelling member for intermittently actuating said valve. Unlike the prior art devices, however, I propose to provide a sound emission control valve which is yieldingly held in a normal open position and is independent of the air expelling member, in that it is not mounted upon or carried by said member and coacting parts on said member and the valve for moving the latter towards a closed position at spaced intervals by the movement of said air expelling member.

It is a further object of my invention to provide a sound-producing device or "voice" as above characterized, wherein the parts are so constructed and relatively arranged, that they will function in an efficient and reliable manner to properly articulate the sound and effect a very realistic simulation of the word syllables.

It is also a further object of the invention to provide a sound-producing device wherein the air compressing and expelling means is arranged within a casing or housing and in which the air is expelled through a suitable reed into an external sound receiving chamber, said chamber having a sound egress opening in its wall and valve means controlling the egress of sound through said opening and having a part extending into said casing and actuated by the air expelling means.

With the above and other objects in view, the invention consists in the improved sound-producing device and in the form, construction and relative arrangement of its several parts as will be hereinafter more fully described, illustrated in the accompanying

drawings and subsequently incorporated in the subjoined claims.

In the drawing wherein I have illustrated one simple and practical embodiment of my invention and in which similar reference characters designate corresponding parts throughout the several views,

Figure 1 is a vertical sectional view, taken on the line 1—1 of Figure 3, illustrating one practical embodiment of the device and showing the weighty member in position at the start of its air expelling movement,

Figure 2 is a similar view showing an intermediate position of said air expelling member,

Figure 3 is an end elevation, and

Figure 4 is a horizontal section taken on the line 4—4 of Figure 1.

Referring more particularly to the drawing wherein I have illustrated an embodiment of the invention, which will give very satisfactory results in practice, the casing or housing 5 may conveniently consist of a suitable length of rigid cardboard tubing to one end of which a closure plate 6 of any suitable form is applied. Within this casing there is enclosed an air receiving chamber. This chamber is preferably in the form of a bellows having a flexible tubular wall 7, gradually increasing in diameter from one end to the other thereof and at its latter end having the edge portion outwardly turned over and around the other end edge of the casing wall 5, as shown at 8. The edge of a metal plate 9 is engaged upon this out-turned edge 8 of the bellows wall and constitutes the fixed head of the bellows.

The other end head of the bellows is movable within the casing 5 and consists of a weighty metal disc 10 having a central opening 11 therein. The underside of this weighty member is recessed, as at 12, to receive the other end edge of the tubular bellows wall 7 which is frictionally clamped against the walls of said recess by a disc 13 of fiber, or other suitable material inserted within the smaller end of said tubular wall. This disc likewise is provided with an opening 14 of the same diameter concentrically related to the opening 11. At the lower side of this opening 11, in the member 10, a flexi-

ble washer member 15 is arranged, the member 10 having an annular rabbet 16 surrounding said recess to receive the edge of said washer. This flexible washer may be 5 readily stamped or cut out from heavy felt or other material and is provided with a central opening 17 therein of relatively small diameter and in concentric relation with the openings 11 and 14.

10 A sheet metal member 18 is disposed exteriorly of the casing 5 at one end thereof and provides a sound receiving chamber open upon one side, surrounded by the annular wall of said member, said wall being 15 formed upon its edge with an annular channeled bead 19 receiving the edge of the metal plate 9 and constructed to tightly clamp the edge of said plate and the end of the tubular bellows wall 7 against the end of the 20 casing wall 5.

The end wall 20 of the chamber 18 which is spaced from the plate 9, is centrally formed with an inwardly pressed, concavo-convex or cupped section 21 having a central sound egress opening 22 therein. The wall of this cup 21 at the outer side thereof is formed with an annular shoulder against which the end of the metal disc 23 is tightly seated, said disc having a plurality of openings 24 therein through which the sound is 30 finally emitted from said cup.

The plate 9 carries a suitable sound producing device or reed, indicated at 25, through which the air is expelled from the 35 bellows chamber under the pressure of the weighty member 10. The wall 9 is centrally formed with an opening surrounded by an inwardly turned boss 26, which serves as a guide for the stem or post 27 of a suitable 40 valve 28 operating between the plate 9 and the egress opening 22 in the wall of the cup 21. The end of the valve stem also projects through the latter opening and is surrounded by a coiled expansion spring 29 inter- 45 posed between said valve and the central portion of the metal disc 23. The valve stem or rod 27 also extends loosely through the opening 17 in the flexible washer 15.

The valve rod 27, which extends axially 50 through the bellows chamber has longitudinally spaced lugs or protuberances 30 formed thereon at diametrically opposite points, the purpose of which will clearly appear from the following description.

55 Normally, the spring 29 urges the valve 28 away from the opening 22 to an open position substantially in contact with the fixed head or wall 9 of the bellows, as seen in Figure 2 of the drawings.

60 Assuming that the bellows is fully expanded and the device then inverted so as to position the weighty head or member 10, as shown in Figure 1, said member will immediately tend to drop by gravity, thereby collapsing the bellows wall 7 and expelling the

air from the bellows chamber. However, at the start of this gravity air expelling movement of the member 10, the flexible washer 15 at opposite sides of the opening 17 thereon, engages the first pair of lugs 30 adjacent 70 the end of the valve rod 27. The member 10, however, is sufficiently heavy to force the valve rod 27 and valve member 28 downwardly against the action of spring 29 when

the washer thus engages the lugs 30, so that the valve member is moved to a position adjacent the egress opening 22, as shown in Figure 1 of the drawings and restricts the volume of sound which may pass from the

sound receiving chamber formed by the member 18 through said egress opening. The member 10 will continue to fall by gravity, the washer 15 flexing relative to the valve rod or stem so that the first pair of lugs 30

on said rod will pass through the central opening 17 in said washer. Obviously, however, these lugs apply a certain resistance to the gravity movement of the member 10 and check or impede its descent. During this

time, the sound which is emitted in restricted volume through the opening 22 and openings 24 will simulate the pronunciation of the letter "m". After the first pair of lugs 30 have

passed through the openings 17, the gravity descent of the member 10 is more rapid. Of

course, the spring 29 immediately returns the valve 28 to its fully open position so that during the further descent of the member 10, until the flexible washer strikes the second pair of lugs 30 on the valve rod, sound

will be emitted through the opening 22 and openings 24 in greater volume and simulate the letter "a", thus completing the articulation

of the first syllable "ma". The weight of the member 10 being sustained by the lugs 30, the spring 29 is again compressed and valve 28 moved towards its closed position,

so that during the continued slow descent of member 10, against the resistance offered by the ring 30, in passing through the opening 17 of the flexible washer, the reduced or restricted volume of sound emitted from the

opening 22 and openings 24 again simulates the letter "m" and after the flexible disc 15 becomes free from the lugs 30 and during

the continued descent of the member 10, to its final position of rest, sound is emitted in maximum volume to again simulate the letter "a", thereby completing the articulation

of the second syllable "ma". Of course, it

will be understood that the action above described, occurs in rapid succession, so that the spoken pronunciation of the word "ma

ma" will be simulated in a very realistic manner.

Upon the inversion of the device from the position shown in Figure 2, the weighty member 10 moves in the opposite direction relative to the axially movable valve rod 27,

so that the flexible bellows wall 7 is expand-

ed and the bellows is reinflated. Preferably, I provide the end cover or casing 6 with an air outlet opening 31 to avoid any cushioning effect upon the member 10 during the latter movement thereof.

From the foregoing description, considered in connection with the accompanying drawings, the construction, manner of operation and the several advantages of the device, 10 will be readily understood. It will be seen that the present improvements are primarily characterized by the fact that the sound emission control valve is normally yielding- 15 ly held in an open position and is not mounted upon, or carried by the bellows head or gravity movable air expelling member, as has heretofore been the case. The means which I provide to effect the intermittent actuation of the valve also permits of the valve 20 movement being very accurately controlled, while at the same time, materially simplifying the construction of such actuating means as well as the movable bellows head or air expelling member. The member 18 forming 25 the independent sound receiving chamber, may be simply produced from sheet metal stamping and will not materially add to the manufacturing cost of such devices. While in the accompanying drawings I have illus- 30 trated the air expelling and compressing means in the form of a collapsible bellows, it will be apparent that in so far as the means for articulating the sound is concerned, various other equivalents of this air compressing 35 and expelling means might be substituted. Further, the construction and arrangement of the control valve, as well as the actuating means therefor, might be produced in other alternative structural forms and it will be 40 accordingly understood that in the practical development of the invention I do not consider myself as necessarily restricted to the precise details of form and construction of the various elements as herein disclosed, but 45 reserve the privilege of resorting to all such legitimate changes therein as may be fairly embodied within the spirit and scope of the invention as claimed.

I claim:—

50 1. In a sound producing device, an air receiving chamber and a sound receiving chamber, a sound producing reed, means for expelling air under pressure from said air receiving chamber through the reed and into 55 the sound receiving chamber, a valve controlling the emission of sound from the latter chamber and having a rod extending through the air receiving chamber, and additional means carried by the air expelling 60 means and cooperating with means on said valve rod to actuate the valve and articulate the emission of sound from said sound receiving chamber.

65 2. In a sound producing device, an air receiving chamber and a sound receiving

chamber, a sound producing reed, means for expelling air under pressure from said air receiving chamber through the reed and into the sound receiving chamber, a valve controlling the emission of sound from the latter chamber and having a rod extending through the air receiving chamber, said valve rod having spaced projections thereon, and a yieldable part carried by said air expelling means to successively engage said projections and actuate the valve to articulate the emission of sound from said sound receiving chamber.

3. In a sound producing device, an air receiving chamber and a sound receiving chamber, a sound producing reed, a gravity movable member for expelling air from the air receiving chamber through said reed into the sound receiving chamber, the wall of the latter having an opening therein, a valve associated with said opening and means yieldingly holding said valve in a normal open position, said valve having spaced parts, and a flexible element carried by the air expelling member to engage said spaced parts at intervals during the movement thereof and move said valve towards its closed position to thereby effect an articulated emission of the sound through said opening.

4. In a sound producing device, a casing having an air chamber therein and a gravity movable member for expelling air under pressure from said chamber, a sound receiving chamber exterior to said casing, a sound producing reed through which the air is expelled into said sound receiving chamber, the wall of the latter chamber having an opening therein, a valve associated with said opening and having a rod extending through said air receiving chamber, a spring yieldingly sustaining the valve in a normal open position, and means on said air expelling member adapted to releasably engage the spaced means on said valve rod to move said valve towards its closed position during the air expelling movement of said member to thereby effect an articulated emission of the sound.

5. In a sound producing device, a casing having an internal air receiving chamber and an external sound receiving chamber, said latter chamber having an opening in the wall thereof, a sound producing reed, a gravity movable member within said casing to expel air under pressure from said air receiving chamber through the reed into said sound receiving chamber, a valve associated with said opening and having a rod extending through said air expelling member axially thereof, a spring yieldingly sustaining said valve in open position relative to the opening in the wall of said sound receiving chamber, a flexible washer carried by the air expelling member, through which the valve

rod loosely extends and longitudinally spaced means on said rod adapted for releasable engagement by said washer during the air expelling movement of said member to move said valve towards a closed position relative to said opening and thereby effect the articulated emission of the sound.

6. In a sound producing device, a casing, a bellows within said casing including a flexible tubular wall having a fixed head at one end and a gravity movable head at its other end, a sound receiving chamber at one side of said fixed head of the bellows, a sound producing reed through which the air is ex-

15 pelled from the bellows by said gravity movable member into said chamber, the wall of said chamber having an opening therein, a normally open valve associated with said opening and having a rod extending axially through the bellows and releasable coacting means on said gravity movable bellows head and the valve rod to move said valve towards its closed position at spaced intervals in the collapse of the bellows and thereby effect the articulated emission of the sound. 20

25 In testimony that I claim the foregoing as my invention, I have signed my name hereto.

ANTON L. GRUBMAN.
